FIG-1

FIG-2

FIG-3

To all whom it may concern:

Be it known that we, Kenneth C. Allen, a citizen of the United States of America, residing at Dayton, in the county of Montgomery and State of Ohio, and David A. Meeker, a citizen of the United States of America, residing at Troy, in the county of Miami and State of Ohio, have invented a new, original, and ornamental Design for a Scale, of which the following is a specification, reference being had to the accompanying drawings, forming a part hereof, and in which

Fig. 1 is a perspective view showing the front of a scale embodying our new design;

Fig. 2 is a front elevational view of the scale; and Fig. 3 is a side elevational view of the scale. The characteristic features of the scale reside in the portions shown in full lines.

We claim:

The ornamental design for a scale, substantially as shown and described.
